CLAIM

I claim the ornamental design for an activities table with curved legs, as shown and described.

DESCRIPTION

FIG. 1 is a perspective view of an activities table with curved legs;

FIG. 2 is a top plan view of the table;

FIG. 3 is a bottom plan view of the table;

FIG. 4 is a left elevation view of the table;

FIG. 5 is a right elevation view of the table;

FIG. 6 is a front elevation view of the table; and,

FIG. 7 is a rear elevation view of the table.
